FREDERICK G. STEWART, OF STOCKTON, CALIFORNIA, ASSIGNOR TO THE E. J. WOODISON CO., OF BUFFALO, NEW YORK.

SUSPENSION MEANS FOR POURING DEVICES.

1,289,299.

Specification of Letters Patent.

Patented Dec. 31, 1918.

Application filed December 22, 1917. Serial No. 208,484.

To all whom it may concern:

Be it known that I, FREDERICK G. STEWART, a citizen of the United States, residing at Stockton, in the county of San Joaquin 5 and State of California, have invented a new and useful Improvement in Suspension Means for Pouring Devices, of which the following is a specification.

This invention relates to suspension 10 means for pouring devices used in foundries and the like to pour molten metal into molds of various sorts, and has for its object to provide a device of this character, simple in construction, cheap to manufacture and 15 readily operable and adjustable to any desired position by one person.

Pouring devices of this sort are ordinarily supported from overhead trolleys or like 20 movable carriers which are adapted to travel on tracks, bridges, or the like, so that the molten metal may readily be transported from the furnaces to the various molds. It is highly desirable that the pouring device be readily adjustable to different altitudes 25 for pouring a multiplicity of molds of different sizes, and to prevent any spilling and subsequent wastage of metal quite exact vertical adjustment of the pouring ladle is required.

30 The device as shown and described is especially adapted to small and medium sized work and because of its compactness and simplicity, and particularly because of the ease of adjustment and operation thereof, 35 its use lowers the cost of pouring, materially increases the output, prevents wastage of metal and diminishes the labor necessarily done by the operator of the pouring device.

40 In the accompanying drawings:

Figure 1 is a sectional elevation of a pouring device and the suspension means therefor embodying the invention, attached to its overhead support, taken on line 1-1, Fig. 2.

45 Fig. 2 is an elevation of the suspension means and pouring device taken at right angles to Fig. 1.

The device which forms the subject of the present invention is provided with two distinct 50 adjusting mechanisms which are utilized respectively for fixing the approximate height of the pouring ladle, and for

adjusting the ladle to the exact height required to accomplish the pouring with the highest degree of efficiency. The adjusting 55 devices shown in the drawings are the preferred means employed for such purposes, but it is not intended to limit the invention to the forms shown, and other adjusting mechanism by which the same results may 60 be accomplished can be used in place thereof or if desired.

In the preferred construction shown, the overhead support for the device is shown as comprising a trolley or carrier 3 which 65 is adapted to travel on the track 4. These parts form no part of the present invention, and the suspension device can be used with any other suitable form of overhead support.

70 5 is a suspension rod which is provided with a hooked end 6 adapted to engage with the trolley 3. The lower portion of the rod 5 is preferably forked as indicated at 7, and is provided, preferably at the lower 75 extremity of the rod, with a socket 8 having a screwthreaded opening 9 therein. If desired any other suitable construction of rod can be used instead of the form shown.

75 10 is a supporting bar or member which 80 is also preferably forked, as indicated at 11. 12 is a socket formed preferably at the upper portion of this member and having the screw-threaded opening 13 formed therein.

85 As shown, the preferred adjusting means by which approximate adjustment of the ladle is obtained, consists of a turn-buckle 14 which is located between the rod 5 and the member 10, such turn-buckle being provided with an operating handle 15, and having its upper and lower extremities 16 and 17 provided with a right and left hand thread respectively and adapted to enter respectively the opening 9 of the socket 8 and 95 the opening 13 of the socket 12. This turn-buckle is of well known construction and, as afore set out, other adjusting means may be substituted therefor if desired.

100 The preferred form of auxiliary adjusting means comprises a ratchet segment 18 suitably secured to the member 10 as by rivets 19, and a ratchet lever 20 pivoted at 21 to the member 10, and preferably hav-

ing one extremity thereof bent upwardly as indicated at 22. Any other suitable supplementary adjusting means may be substituted for the ratchet arrangement shown, 5 if desired; nor is it intended to limit the invention to mounting said supplementary adjusting means below the approximate adjusting means and the member 10.

In the preferred construction shown, the 10 end of the ratchet lever 20 is provided with lugs 23 by which a link 24 is supported in such a way as to allow free movement thereof in a vertical plane.

26 represents the usual form of pouring 15 ladle, provided with trunnions 27. 28 is the ladle yoke, the bent ends 29 of which are adapted to hook under the ladle trunnions 27. 30 is an opening formed at the upper portion of the yoke. The link 24 is provided 20 with a shaft or bolt 31 at its lower extremity, having a head 32, and this shaft passes through the opening 30 of the ladle yoke, thus serving to form a swivel connection 25 between the yoke and the suspension device. 33 is a handle of usual form removably attached to the ladle for tilting the same.

The device is adapted for use with any suitable form of pouring ladle and support 30 therefor and if desired such form may be substituted for the ladle and yoke shown.

In operating the device, the approximate height to which it is required to raise the ladle is first fixed by manipulation of the 35 turn-buckle, or the adjusting means which may be used in place thereof, and the exact height required is then secured by adjustment of the ratchet handle or other supplementary adjusting means. In this way perfect 40 adjustment of the ladle can be secured with a minimum amount of effort and much better results are obtainable than when only a single adjusting mechanism is utilized. By swinging the ratchet handle shown in 45 a horizontal plane, either alone or in connection with the handle of the turn-buckle, a corresponding movement is imparted to the ladle, and the swivel joint connection formed between the suspension device and 50 the ladle yoke greatly facilitates the ease with which the ladle can be used in a number of varying positions.

I claim as my invention:

1. In a suspension device, the combination 55 with a ladle and an overhead support, of means for suspending the ladle from the support including means for raising and lowering said ladle to approximately adjust the ladle relatively to the support, and 60 supplementary means for raising and lowering said ladle to accurately adjust the same.

2. In a suspension device, the combination 65 with a ladle and a movable overhead

support, of means for suspending the ladle 65 from the support including means for approximately adjusting the ladle relatively to the support, and supplementary means for accurately adjusting the ladle, and a swivel connection formed between said ladle 70 and the supporting means therefor for enabling said ladle to swing about a substantially vertical axis.

3. In a suspension device, the combination 75 with a ladle and an overhead support, of suspension means secured to said support, a supporting member, screw-threaded means for adjusting the suspension means and the supporting member relatively to one another, and supplementary 80 adjusting means for accurately adjusting the ladle.

4. In a suspension device, the combination 85 with a ladle and an overhead support, suspension means, a supporting member, a turn-buckle connecting said suspension means and supporting member, and a lever pivotally mounted on said supporting member and supporting said ladle and adjustable 90 for raising and lowering said ladle. 90

5. In a suspension device, the combination 95 with a ladle and an overhead support, suspension means secured to said support, a supporting member, a turn-buckle connecting said suspension means and said sup- 100 porting member, a ratchet segment mounted on said supporting member, and a ratchet lever on which said ladle is suspended and which is adapted to interlock with said ratchet segment.

6. In a suspension device, the combination 105 with a ladle and an overhead support, suspension means secured to said support, a supporting member, a turn-buckle connecting said suspension means and said sup- 110 porting member, a ratchet segment mounted on said supporting member, a ratchet lever adapted to interlock with said ratchet segment, and swivel means connecting the ladle and the ratchet lever. 110

7. In a suspension device, the combination 115 with a pouring ladle and a movable overhead support, a suspension rod provided with means for attaching said rod to the overhead support, a supporting member, adjusting means connecting the suspension rod and the supporting member where- 120 by said rod and said member may be adjustably related to one another, auxiliary adjusting means mounted on said support- 125 ing member comprising a ratchet segment and a ratchet lever having an operating handle at one end thereof, a link movably secured at the opposite end of said ratchet lever and adapted to swing in a vertical 125 plane, and a swivel connection between said ladle and said link.

8. In a suspension device, the combina-

tion with a pouring ladle and an overhead carrier, a rod member adapted to be suspended from said carrier, a lower supporting member, means connecting the rod member and the lower member whereby said members may be relatively adjusted, a ladle yoke adapted to support said ladle, supplementary adjusting means mounted on the lower member, a link pivoted at one end 10 of said supplementary adjusting means

adapted to swing in a vertical plane, and a swivel connection between said link and said ladle yoke.

Witness my hand, this 11th day of December, 1917.

FREDERICK G. STEWART.

Copies of this patent may be obtained for five cents each, by addressing the "Commissioner of Patents, Washington, D. C."

It is hereby certified that in Letters Patent No. 1,289,299, granted December 31, 1918, upon the application of Frederick G. Stewart, of Stockton, California, for an improvement in "Suspension Means for Pouring Devices," an error appears in the printed specification requiring correction as follows: Page 2, lines 118-119, claim 7, for the words "adjustably related" read "*adjusted relatively;*" and that the said Letters Patent should be read with this correction therein that the same may conform to the record of the case in the Patent Office.

Signed and sealed this 28th day of January, A. D., 1919.

[SEAL.]

R. F. WHITEHEAD,

Acting Commissioner of Patents.
